PILLOW CONSTRUCTION

Mildred J. Jackson, 549 W. Allen St., Springfield, Ill.
Filed May 7, 1963, Ser. No. 278,696

1 Claim. (Cl. 5—337)

This invention relates to a pillow construction and more particularly to a pillow formed of a plurality of individual layers removably secured to each other to form a stacked headrest which is extremely soft and flexible and therefore particularly comfortable.

As conducive to a better understanding of the instant invention it should be understood that it is necessary for many women to sleep with their hair in curlers or the like in order to maintain a set or chosen curl without unnecessarily time consuming combing and brushing operations each morning. Such curlers or rollers are often-times extremely large, particularly for producing the bouffant hairdos currently in fashion. Also, they frequently have a toothed or spiny surface to facilitate holding the hair in place. It will be readily seen that the utilization of such implements is extremely uncomfortable making it difficult for a woman to sleep with the same in her hair.

It is, therefore, a primary object of this invention to provide a pillow construction which is particularly soft and flexible so that the rollers or curlers may sink into the surface of the pillow to thereby ease the pressure on head of the user.

Another object of the instant invention is the provision of a pillow construction having a plurality of individual layers which are removably securable to each other to readily vary the thickness thereof to accommodate various sizes of curlers or rollers and to satisfy the specific needs of the user.

A further object of this invention is to provide a pillow construction formed of a plurality of individual layers, each layer being quilted to increase the softness and flexibility of the combined construction.

Yet another object of the instant invention is to provide such a pillow which may be produced in any of a variety of sizes and shapes and which therefore will offer great flexibility in use.

A still further object of this invention is to provide a pillow construction formed of a plurality of individual layers and a variety of specific means for removably securing the plurality of layers to each other.

Other and further objects reside in the combinations of elements, arrangements of parts, and features of construction.

Still other objects will in part be obvious and in part be pointed out as the description of the invention proceeds and as shown in the accompanying drawing wherein:

FIGURE 1 is a top plan view of one layer of a pillow construction in accordance with the instant inventive concept;

FIGURE 2 is a transverse cross-sectional view taken substantially on line 2—2 of FIGURE 1;

FIGURE 3 is a side elevational view of the layer illustrated in FIGURE 1;

FIGURE 4 is a side elevational view similar to FIGURE 3 but showing a layer of increased thickness;

FIGURE 5 is a side elevational view similar to FIGURES 3 and 4, but showing a layer of still greater thickness;

FIGURE 6 is a side elevational view showing a plurality of individual layers removably secured together by a flexible member tied through vertically aligned loops spaced about the periphery of each layer;

FIGURE 7 is a top plan view of a modified layer for

2

the pillow construction of the instant invention which is square in form;

FIGURE 8 is a top plan view of another modified layer for the instant pillow construction which is rectangular in form and substantially similar to the conventional bed pillow;

FIGURE 9 is a fragmentary perspective view of an individual layer for the pillow construction of the instant invention showing the use of a button and a tab with a buttonhole as a securing means;

FIGURE 10 is a fragmentary perspective view similar to FIGURE 9 illustrating the use of snaps and an elongated tab means for securing individual layers together; and

FIGURE 11 is a fragmentary perspective view similar to FIGURES 9 and 10 of a curved pillow layer showing the use of eye means and an elongated tab carrying hook means to secure the layers to each other.

Similar reference characters refer to similar parts throughout the several views of the drawing.

Referring now to the drawing and more particularly to FIGURES 1 to 3, an individual layer for the pillow construction of the instant invention is indicated generally by the reference numeral 20 and is shown as substantially rectangular in form, having an upper and lower covering 22 and 24, respectively, formed of any conventional material, nylon being preferable, and containing therewithin a filling 26 also formed of any conventional material, a polyester such as Dacron, a product of Du Pont, being found most satisfactory. The coverings 22 and 24 are sewn about their periphery at 28 and are preferably quilted as indicated at 30 to increase their flexibility and softness.

Each of the layers may be formed in varying thicknesses as indicated at 20a and 20b in FIGURES 4 and 5, respectively.

Each layer has a plurality of means spaced about its periphery for removably securing a selected number of the same together. One embodiment of such means is shown at 32 to comprise loops formed of a flexible material such as cord or the like secured to each corner of each layer and adapted to be vertically aligned as shown in FIGURE 6 when a plurality of layers are stacked one upon the other, to receive therethrough a flexible member 34 which may be tied into a bow as shown at 36.

The use and operation of the pillow construction of the instant invention will now be apparent. Any number of desired layers may be superimposed or stacked as illustrated in FIGURE 6 and the flexible members 34 may then be secured through the loops 32 to maintain the plurality of layers in a fixed relationship. Whenever it is desired to vary or change the number of layers utilized, the flexible member 34 may be readily untied and layers 20 removed or added as necessary.

Each layer may be formed in any desired size and shape, a substantially square layer being indicated at 20d in FIGURE 7 and a substantially rectangular layer, similar in form to a conventional bed pillow, being shown at 20e in FIGURE 8.

The modification of FIGURE 8 is shown as having a button 38 secured at each of its corners to cooperate with an elongated tab means (not shown) having a plurality of spaced buttonholes defined therein for engaging vertically aligned buttons 38 on stacked layers.

A slight modification is shown in FIGURE 9 at 20f wherein a button 40 and a tab means 42 having a buttonhole 44 defined therein is secured to each corner of each layer, the buttonhole 44 being engageable with a similar button 40 on the next lower layer when the layers are stacked as shown in FIGURE 6.

The modification shown in FIGURE 10 at 20g has one-half of a conventional snap means secured to each corner of each layer (not shown) with a plurality of cooperating other halves 46 being secured in spaced relationship to an elongated tab means 48. The tab means 48 may be made in a variety of lengths depending upon the number of layers to be utilized or it may be made in a single length with extra snap means 46 hanging free. The snap means may be readily engaged when a plurality of layers are stacked as shown in FIGURE 6 to align the corners thereof.

A still further modification is shown in FIGURE 11 at 20h and is illustrated as curved to indicate that a circular or oval pillow construction may be readily provided. In this embodiment a plurality of eye means 50 are secured around the periphery of each layer in spaced relationship and a tab means 52 is provided having a plurality of vertically spaced hook means 54 for cooperating with vertically aligned eye means 50 on a plurality of stacked layers in an obvious manner.

It will now be seen that there is herein provided a pillow construction which satisfies all of the objects of the instant invention and others, including many advantages of great practical utility and commercial importance.

Since many embodiments may be made of the instant inventive concept and since many modifications may be made in the embodiments hereinbefore shown and described, it is to be understood that all matter herein is to be interpreted merely as illustrative, and not in a limiting sense.

I claim:

A pillow construction comprising a plurality of super-

imposed similar individual bed pillows each of which comprises a pair of similar upper and lower covers with the annular outer sections thereof in face to face contact, stitching by which said annular outer sections are sewn together to provide a container for a soft flexible piling, said stitching being disposed inwardly of the periphery of said covers to provide an annular outwardly extending flange about said container; and securing means by which a plurality of superimposed pillows are detachably connected together, said securing means comprising a plurality of annularly spaced buttons secured to said flange, a plurality of tabs having the upper ends thereof secured to said flanges, one of said tabs extending downwardly from each of said buttons, a button hole formed in the lower free end of each of said tabs through which the buttons secured to the flange of an adjacent lower pillow are inserted to detachably secure said adjacent pillows together.
